UNITED STATES PATENT OFFICE.

MAURICE CHASTENET, OF BORDEAUX, FRANCE, ASSIGNOR TO CHASTENET
FRÈRES, OF BORDEAUX, FRANCE.

DESIGN FOR A BOTTLE.

No. 37,820.

Specification for Design.

Patented Feb. 13, 1906.

Application filed October 11, 1905. Serial No. 282,345. Term of patent 14 years.

To all whom it may concern:

Be it known that I, MAURICE CHASTENET, a citizen of the Republic of France, residing at Bordeaux, France, have invented a new, original, and ornamental Design for Bottles, of which the following is a specification, reference being had to the accompanying drawing, forming part thereof.

The drawing illustrates my invention in front elevation.

My invention consists in an ornamental bottle having the general form and characteristics as shown in the accompanying drawing.

I claim—

The ornamental design for a bottle, as shown.

MAURICE CHASTENET.
